(57) **CLAIM**

We claim the ornamental design for a case for a computing
device, as shown and described.

DESCRIPTION

FIG. 1 is a front perspective view of the case for a computing
device;

FIG. 2 is a back perspective view of the case for a computing
device shown in FIG. 1;

FIG. 3 is a back plan view of the case for a computing device
shown in FIG. 1;

FIG. 4 is a front plan view of the case for a computing device
as shown in FIG. 1;

FIG. 5 is a right plan view of the case for a computing device
as shown in FIG. 1;

FIG. 6 is a left plan view of the case for a computing device
as shown in FIG. 1;

FIG. 7 is a bottom plan view of the case for a computing
device as shown in FIG. 1; and,

FIG. 8 is a top plan view of the case for a computing device
as shown in FIG. 1.

The features shown in broken lines and any surfaces of the
design not shown, including interior surfaces, form no part
of the claimed design. The dot-long dash-dot line represents
a boundary of the claim.
